UNITED STATES PATENT OFFICE.

HENRY W. YOUNGQUIST, OF MANCHESTER, NEW HAMPSHIRE, ASSIGNOR TO DRAPER CORPORATION, OF HOPEDALE, MASSACHUSETTS, A CORPORATION OF MAINE.

WEFT-REPLENISHING MECHANISM FOR LOOMS.

1,396,154.

Specification of Letters Patent.

Patented Nov. 8, 1921.

Application filed August 21, 1919. Serial No. 318,869.

To all whom it may concern:

Be it known that I, HENRY W. YOUNGQUIST, a citizen of the United States, residing at Manchester, in the county of Hillsborough, State of New Hampshire, have invented a certain new and useful Improvement in Weft-Replenishing Mechanism for Looms, of which the following is a specification, reference being had therein to the accompanying drawings.

The invention is for employment in loom-mechanisms of the class effecting replenishment of the loom-shuttles by introducing into a shuttle needing replenishment a filling-carrier loaded with weft or filling. It provides improved means for controlling a filling-carrier during transfer from the magazine or feeder containing the reserve supply of loaded filling-carriers to the shuttle. It provides also for centering the filling-carrier and its load of filling widthwise with reference to the shuttle, and for preventing longitudinal displacement of the filling-carrier.

One characteristic feature of the invention consists in providing yieldable means which permits the carrier-engaging portion of the controlling means to shift so as to compensate for any initial want of perfect register of the said engaging portion with the head of the leading filling-carrier in the magazine or feeder, occupying its waiting position against the end-stop. The said yieldable means, *i. e.*, capacity for shifting, compensates also for any want of perfect register of the head of a descending carrier with relation to the surfaces inside the shuttle between which it should enter, by allowing the engaging portion and carrier to move either rearward or forward so as to accommodate the carrier-head to the position of the said surfaces. Also, it compensates for any movement of the shuttle either forward or rearward, due to the swing of the lay, which may take place after the carrier-head has begun its entrance between the said surfaces, while the controlling device remains in engagement with the said head.

The feature just mentioned is of importance in those cases in which it is required that a filling-carrier contained within a shuttle should have a certain predetermined position, rotatively considered. For example, in looms provided with certain

forms of the depletion-detectors known as filling-feelers use is made of bobbins that are constructed with special features for coöperation with the said feelers. For the proper action of the feelers, correct presentation of the said features with reference to the feeler-members is necessary. That necessity exists when a bobbin is formed with a recess or slot intended to be entered in a feeling action by the feeler-member as soon as said recess or slot is uncovered by reason of the substantial exhaustion of the filling-supply carried by the bobbin. When occupying the shuttle the bobbin should be so positioned rotatively as to present the recess or slot in line with the feeler-member; otherwise the feeler-member will not enter the recess or slot when the uncovering takes place, and the intended function of the feeler will not be performed.

A second feature of invention is that of so locating the engaging portion of a controlling device that it enters the shuttle entirely beyond the jaws in the latter which take hold of the head of the filling-carrier. This location enables the said engaging portion to pass completely down within the chamber of the shuttle without striking the shuttle-jaws. It also enables the engaging portion to be proportioned so as to extend more completely across the diameter of the head of the filling-carrier than otherwise would be practicable, alongside and beyond the longitudinal axis of the filling-carrier, thereby rendering the controlling device more efficient in restraining the filling-carrier from turning around said axis during the transferring operation.

The feature of invention which provides for centering the filling-carrier and its load of filling widthwise of the shuttle in entering the same consists in providing jaws to pass down at opposite sides of the filling-carrier between the ringed head of the latter and its barrel, and longitudinal displacement of the entering filling-carrier relative to the shuttle is prevented by engagement of said jaws with shoulders on the filling-carrier adjacent the ringed head.

A device embodying the different features of the invention provides in advantageous manner for placing a bobbin in a shuttle in the required position, and at the same time overcomes a number of practical difficulties.

The said features may be used separately, and the physical embodiment of the principles and features of the invention may vary more or less in construction and in the relations of the parts.

Figure 1 shows one form of embodiment, in connection with certain of the main parts of a weft-replenishing mechanism and adjacent portions of the loom proper, the rotary part of the magazine or feeder being in section from front to rear.

Fig. 2 is a rear elevation of the hammer or transerrer and controlling device of Fig. 1, together with a filling-carrier and a portion of the loom-shuttle in longitudinal section.

Fig. 3 is a view of the hammer or transerrer and controlling device looking from the side opposite that shown in Fig. 1, with a filling-carrier head in cross-section.

Fig. 4 is a view in elevation of a filling-carrier, in this instance a bobbin, showing the slot therein.

Fig. 5 is a top view of the said filling-carrier.

Fig. 6 is an end view of the head thereof.

The features of the invention are embodied in and in connection with the controlling device E, Figs. 1, 2 and 3, that moves in unison with and in this instance is mounted upon the hammer or transerrer 11. I will explain the said features after first referring to certain parts of the general organization of the loom and its replenishing mechanism, not themselves included in the invention but with which the said controlling device is associated in use.

The loom-frame 1, lay-sword 2, lay-beam 3, shuttle-box front 4 and back 5, the stand 6 fixed upon the loom-frame at one end of the breast-beam, end-plate 6^a integral with said stand 6, and stud 7 projecting outward from end-plate 6^a, and the butt-holding plate 8 and connected ratchet-wheel 9, both integral with the elongated hub 10 sleeved upon the said stud, all being old and well-known, need no extended description. The same is true respecting the hammer or transerrer 11, except in so far as the latter is modified in applying the invention thereto, it being shown sleeved as usual upon the stud 12 projecting outward from the said stand, and also as having as usual connected pivotally to its downwardly-extending arm 11^a the latch 13 which is engaged by the finger 14^a of the shuttle-feeler 14 so that the position of the said latch and the time of its engagement by the bunter 15 carried by the lay are controlled through the shuttle-feeler. It also is true respecting the indicating rockshaft 16 mounted in bearings at the front of the loom, such rockshaft being controlled by the filling-detector devices of the loom and itself controlling by means of its arm 17 the positions of the shuttle-

feeler 14 and latch 13 and thereby controlling the engagement of the latch by the bunter 15 when the lay beats up. As is well-known, when such engagement occurs the hammer or transerrer 11 is actuated to transfer the leading filling-carrier b in the magazine or feeder, from its position against the end-stop 18, down downward past the yielding gate 19 into the shuttle 20 on the lay. Fig. 1 of the drawings shows a dog or pawl 21 of well-known character, carried by the hammer or transerrer 11, and engaging with the teeth of the ratchet-wheel 9 so that as the hammer or transerrer rises after having been swung downward for a transferring action the said dog or pawl turns the rotary part of the magazine or feeder to bring the next reserve bobbin against the end-stop 18, and 22 is an old form of holding or detent-pawl pivoted upon the stand 2 and also engaging with the teeth of said ratchet-wheel 9 to prevent the rotary part of the magazine or feeder from turning backwardly.

The bobbin b, Figs. 2 to 6, having a feeler-slot b', Fig. 4, and provided with rings b² surrounding its head, and having its butt-end b³ beyond the said rings slabbed off on both sides of the bobbin-axis at right-angles with the feeler-slot, is as heretofore with the exception of having its head also slabbed off at b⁴, b⁴, between the rings b² and the bobbin-barrel. The shuttle 20 is as heretofore with its feeler-slot 20^a shown in Fig. 2, its grooved spring jaws 21 (only one shown) for engaging the ringed head of the bobbin, its incline 22 for deflecting the bobbin endwise within the shuttle, and its secondary jaws 23 (only one shown) for engaging with the flat sides of the slabbed-off butt-end b³ of the bobbin to cause the feeler-slot b' of the bobbin to register with the feeler-slot 20^a of the shuttle while the bobbin is in place within the shuttle.

As is usual when feeler-bobbins having slots are employed, the butt-holding plate or disk 8 of the rotary magazine or feeder is formed with radial parallel-sided slots 8^a into which the slabbed-off butt-ends of the bobbins fit, so that while in the magazine or feeder the slots face in a particular direction.

The controlling device E, in this particular embodiment of the invention mounted upon the hammer or transerrer itself (but not necessarily so in all cases) has jaws e, e, which in the normal upraised position of the hammer or transerrer, as shown in Fig. 1, occupy positions above the leading bobbin b resting against the end-stop 18. At the beginning of the downward movement of the hammer or transerrer the said jaws pass down on opposite sides of the slab-sided portion b⁴ of the bobbin as in Fig. 3, and through their engagement with the flat-

tened surfaces of such portion during the descent of the bobbin toward the shuttle they control the bobbin so as to prevent independent rotative movement thereof.

5 After the bobbin has been placed in the shuttle it is controlled by means of the shuttle-contained secondary jaws 23, Fig. 2, so as to keep the feeler-slot b' thereof in register with the feeler-slot 20^a in the front 10 wall of the shuttle-body.

In accordance with the invention I confer upon the jaws e , e , a yieldability which as stated at the outset in this specification is one characteristic of the invention. In the 15 illustrated embodiment of the invention this yieldability is secured by the employment of a spring-controlled controlling device E that is mounted upon its carrier (the hammer or transerrer) with capacity to yield 20 both forwardly and rearwardly thereon. The capacity for movement is provided for by making the body e' of the controlling device as a flat piece, forming a guideway in the head of the carrying member (ham- 25 mer or transerrer), and fitting said flat piece into said guideway. The body e' is held in the said guideway by means of a screw e^2 , Figs. 1 and 3, extending transversely through the said head, and of a stud 30 e^5 that extends rearwardly from a depend- ing lug on the main arm of the hammer or transerrer. The transversely-extending screw e^2 occupies a slot e^3 (dotted lines Fig. 3) in such body of sufficient length to per- 35 mit the required extent of longitudinal sliding movement of the controlling device. The stud e^5 enters a hole that is formed in a lug e^6 projecting down from the body e' . The capacity for yielding in both directions 40 is secured through the employment of spring-tension for centering the controlling device in an intermediate position. Thus I have shown an expanding spiral spring e^4 surrounding the stud e^5 acting expansively 45 against the lug e^6 of the body e' to hold the controlling device rearwardly, and keeping a lateral projection e^7 , Fig. 1, thereof in contact with a yielding stop con- 50 stituted by one arm of a bent spring e^8 mounted on the corresponding side of the said main arm of the hammer or trans- 55 ferrer. At e^9 is shown a pin projecting from such arm and serving to define the normal position of the said yielding stop. 60 The ends of the jaws e , e , of the controlling device are rounded or beveled at their inner sides to render the engaging portion of the controlling device bell-mouthed so as to facilitate entry of the portion b^4 of a 65 bobbin between the said jaws.

It will be perceived that by the conjoint action of the two springs e^4 and e^8 the controlling device will be maintained ordinarily in its normal position, represented in Figs. 1 and 3, upon the hammer or transerrer,

but the spring e^4 will yield to permit forward movement of the controlling device when sufficient pressure to overcome the resistance of such spring acts in a forward direction against the front jaw e (the left- 70 hand jaw in Fig. 1), while the spring e^8 will yield to permit rearward movement of the said device when sufficient pressure to overcome the resistance thereof acts in a rearward direction against the rear jaw e . 75

The preferred location of the engaging portion of the controlling device is illus- 80 trated in Fig. 2, in which the jaws e , e , are shown as so located upon the hammer or transerrer that in entering the shuttle they will do so entirely beyond the portions of the carrier-head-engaging jaws 21, which are engaged with the ringed portion of the carrier-head. Consequently, no matter how deeply the said jaws may pass down into 85 the chamber of the shuttle they will not strike upon the said jaws. The length of jaw which I am enabled to use by reason of this location is illustrated in Fig. 3.

The employment of jaws e , e , passing 90 down at front and rear, respectively, of the filling-carrier at the inner side of the head of the latter, *i. e.*, between the said head and the barrel of the filling-carrier, effects the centering of the said 95 barrel and its load of filling widthwise of the shuttle in entering the same. The engagement of the said jaws with the shoulders that are produced at the said inner side by slabbing-off the filling-carrier at 100 b^4 , b^4 , prevents longitudinal displacement of the entering filling-carrier toward the eye-end of the shuttle. By reason of this engagement, the usual vertical grooving of the end-stop 18, and shoulder on the head of 105 the hammer or transerrer, to prevent the said longitudinal displacement, are rendered unnecessary and may be dispensed with if deemed desirable. The said shoulder has been omitted in the case of the illustrated 110 construction.

What is claimed as the invention is:—

1. In weft-replenishing mechanism for looms, a transerrer having filling-carrier controlling means yieldably mounted there- 115 upon to permit compensating self-adjust- ment upon engagement with said filling carrier and during transfer.

2. In weft-replenishing mechanism for looms, a transerrer having filling-carrier controlling means movably mounted there- 120 upon, and means for yieldingly keeping said controlling means in a predetermined nor- mal position.

3. In weft-replenishing mechanism for 125 looms, a transerrer having filling-carrier controlling means movable forward and rearward relative thereto, and means for yieldingly, keeping said controlling means normally in an intermediate position. 130

4. In weft-replenishing mechanism for looms, a transerrer having combined therewith means for rotatively controlling a filling-carrier at time of transfer, and means for yieldingly keeping said controlling means normally in an intermediate position.
5. In weft-replenishing mechanism for looms, a transerrer having movably mounted thereupon, positioning jaws adapted to embrace a portion of the filling-carrier at the time of transfer, and means for yieldingly keeping said jaws in a predetermined normal position.
- 15 6. In weft-replenishing mechanism for looms, a transerrer provided with jaws which control a filling-carrier rotatively at time of transfer, movable forward and rearward in unison and means for yieldingly keeping said jaws normally in an intermediate position.
- 20 7. In a weft replenishing mechanism, a transerrer having a filling carrier control-

ling device comprising clamping jaws which engage opposite sides of the filling carrier 25 between the head and the filling carrying portion and enter the shuttle beyond the jaws of the latter whereby rotation of the filling carrier during transfer is prevented.

8. In a weft replenishing mechanism, a transerrer having a filling carrier controlling device comprising yieldable clamping jaws which engage opposite sides of the filling carrier between the head and the filling carrying portion and enter the shuttle 35 beyond the jaws of the latter whereby rotation of the filling carrier during transfer is prevented and means for keeping said yieldable jaws normally in a predetermined position.

In testimony whereof I affix my signature in presence of two witnesses.

HENRY W. YOUNGQUIST.
